MACHINE FOR PRESSING THE BOTTOMS
OF SHOESAndrew Eppler, Jr., Lynn, Mass., assignor to
United Shoe Machinery Corporation, Flemington, N. J., a corporation of New Jersey

Application December 16, 1947, Serial No. 792,026

14 Claims. (Cl. 12—127)

1

This invention relates to machines for applying pressure to the bottoms of shoes, and more particularly to means for supporting a shoe in the pressure-applying operation, the term "shoe" being generally used herein with reference to a shoe mounted on a last. The invention is illustrated herein as applied to a machine for progressively leveling the bottom of a shoe although it should be understood that it is not limited in its application to machines of the particular type illustrated.

In Letters Patent of the United States No. 2,328,572 granted September 7, 1943, on an application of Lloyd G. Miller, there is illustrated a jack for supporting a shoe in the leveling operation employing a toe support, a heel support and an intermediate support for the cone of the last. This intermediate or cone support is movable heightwise of the shoe to a position determined by the shoe when the shoe is positioned on the jack and upon movement of the jack to carry the shoe beneath the leveling roll the cone support is forced more firmly against the last or shoe thereby to provide adequate support for the intermediate portion of the last. Whereas the heel support in such machines is made adjustable with respect to the toe support to accommodate shoes of different sizes, heretofore no provision has been made for similarly adjusting the cone support. Accordingly, it has been found necessary to provide several jacks in cases in which the leveling machine is to operate on a wide range of sizes, the relation between the cone support and the toe support in the different jacks being different to accommodate shoes in different size ranges.

It is an object of the present invention to eliminate the necessity of changing jacks in machines of this type by providing means for adjusting the position of the cone support during the relative adjustment of the heel support and the toe support. To this end and in accordance with a feature of the invention, the cone support is mounted for movement in a direction lengthwise of a shoe on the jack, the adjustment preferably taking place during the adjustment of the heel support. In order to maintain the proper relationship between the heel and toe supports and the cone support, the cone support is movable at a different rate from that of the heel support so that regardless of what size shoe is being operated upon, the cone support will engage the cone of the last in substantially the same relative position. In accordance with another feature of the invention provision is made for moving the cone support heightwise of the heel and toe supports during the adjustment of the

2

jack for different sizes of shoes in order to compensate for different heights of cones of the lasts so that the initial position of the cone support, when the shoe is placed on the jack, will not be excessively higher than that to which it is depressed upon jacking the shoe.

The above and other features of the invention, including novel combinations of parts and details of construction, will now be described by reference to the accompanying drawings and pointed out in the claims.

In the drawings,

Fig. 1 is a side elevation partly in section of a portion of a machine in which the invention is embodied;

Fig. 2 is a side elevation of a portion of the mechanism for operating the cone support;

Fig. 3 is a front elevation of the cone support looking in the direction of the arrows III—III of Fig. 1; and

Fig. 4 is a section on the line IV—IV of Fig. 1.

The invention is illustrated herein as applied to a leveling machine of the type illustrated in Letters Patent of the United States No. 1,667,761 granted May 1, 1928, on an application of E. E. Winkley et al. The machine includes a shoe support or jack comprising a heel post 10 and a toe post 12 carrying means for supporting a shoe and last for the leveling operation performed by a roll 14 that applies downward pressure on the shoe sole and acts progressively along the shoe bottom as the jack is swung by power-operated means in directions lengthwise of the shoe. The heel post carries a spindle 16 arranged to enter the spindle hole in the heel end of the last, the spindle being mounted on a block 18 pivoted at 20 on an upward extension of the heel post for swinging movements lengthwise of the shoe. The spindle 16 extends through an enlarged opening in a plate 22 carried by the block 18, the plate being free to tip about an axis extending laterally of the shoe to adjust itself to the top face of the heel end of the last. The block 18 is connected by a link 24 to mechanism (not shown) whereby the block and spindle may be swung in a clockwise direction by depressing an arm 26 to press the toe end of the shoe firmly down upon toe-supporting means carried by the toe post, as disclosed more fully in Letters Patent of the United States No. 1,719,158 granted July 2, 1929, upon an application of E. E. Winkley et al. The toe-supporting means comprises a member 28 adjustable on arcuate guideways on the toe post 12 and has mounted thereon a block 30 adjustable upwardly and downwardly by a wedge 32 as shown more clearly in Letters Patent of the

United States No. 1,962,141 granted June 12, 1934, on an application filed in the name of A. Eppler. Supported on the block 30 is a toe rest comprising a rubber pad 34 hollowed out to receive the toe end of a shoe, and a holder 36 by which the pad is carried. The holder 36 is mounted on the block 30 for self-adjustment relatively to the shoe about an axis extending laterally of the shoe and located substantially at the shoe-engaging face of the pad 34.

The jack is fulcrumed upon a shaft 38 in suitable bearings, one of which is indicated at 40, in the frame of the machine. The heel post 10 of the jack is fulcrumed upon the toe post at 42 and is adjustable relatively thereto by a threaded adjusting member 44. Mechanism is provided for adjusting the travel of the jack by the operating mechanism in accordance with adjustment of the heel post relatively to the toe post so that the length of travel will correspond with the length of the shoe being operated upon. Mechanism for accomplishing this is illustrated and described in Letters Patent of the United States No. 1,239,664 granted September 11, 1917 on an application filed in the name of W. C. Baxter. Such mechanism includes an arm 46 extending rearwardly from the heel post 10 and connected by a link 48 to an arm 50 of a bell crank lever 52 fulcrumed upon the toe post at 54. The other arm of the bell crank lever operates mechanism such as described in the Baxter patent for varying the length of travel of the jack in accordance with the size of the shoe being operated upon.

The last is supported between its heel end and forepart by a cone support 60. This cone support comprises a pad 62 of rubber or the like arranged for engagement with the cone of the last and is mounted in the upper end of a holder 64. As shown in Fig. 3 this holder comprises a pair of bars 66 provided with reinforcing ribs 68 and a crossbar 70 by which the bars 66 are connected near their upper ends. To the upper ends of the bars 66 are pivoted rearwardly extending arms 72 on threaded bearing studs 74. These studs pass through the bars 66 and into the crossbar 70 thereby to connect the parts together. The rearward ends of the arms 72 are pivoted by threaded bearing studs 76 (Fig. 4) to a bar 78 which is in turn provided with a downwardly extending screw 80 by which the bar 78 is connected to the upwardly extending arm 82 (Fig. 1) of a bell crank lever 84. This bell crank lever is pivoted at 86 to a bracket 88 extending rearwardly from the toe support. A rearwardly extending arm 90 of the bell crank lever 84 is connected by a link 92 to the arm 50 of the bell crank lever 52.

The lower end of the holder 64 is pivotally connected by a pin 94 to the lower end of a slide 96 movable vertically in a slideway formed in a boss 98 on the block 30. Integral with the slide 96 is a rack 100 which meshes with a pinion 102 keyed to a shaft 104 journaled in the boss 98. Secured to the shaft 104 is one end of a spring 106 (Fig. 3) the other end of the spring being connected to a handle 108 which may be secured to the boss 98 in any one of a plurality of positions by any suitable means, to vary the action of the spring 106 on the shaft 104. This spring acts to turn the shaft 104 in a clockwise direction, as viewed in Fig. 1, thereby to urge the holder 64 with the pad 62 upwardly.

Secured to the shaft 104 is a ratchet 110 (Fig. 3) arranged for engagement with which is a pawl 112 carried by an arm 114 rotatably supported at the outer end of a projection 116 ex-

tending laterally from the block 98. The pawl 112 is held out of engagement with the teeth of the ratchet 110 by a shield 118 when the jack is in its loading position. Thus the slide 96 with the rack 100 is free to move vertically. When the shoe is placed on the jack the pad 62 normally occupies a position above that which it occupies when the shoe is jacked so that the pad must be moved downwardly to permit placing a shoe in position on the jack. When the jack starts its rearward movement at the beginning of the leveling operation the arm 114 is moved in a clockwise direction and the pawl 112 moves off the shield 118 into engagement with the teeth of the ratchet 110 thereby locking the slide 96 against downward movement and then upon further movement of the arm 114 in the same direction the slide 96 is moved upwardly to force the pad 62 more firmly against the last. For a more complete description of the parts described above, reference may be had to Letters Patent of the United States No. 2,104,739 granted January 11, 1938 on an application filed in the name of A. Eppler et al.

For thus moving the arm 114 in a clockwise direction at the beginning of the leveling operation mechanism similar to that shown in the Miller patent referred to above is employed. This mechanism includes a pair of toggle links 120, 122 (Figs. 1 and 2), the link 120 being pivoted to the lower end of the arm 114 and the link 122 being fulcrumed on the toe post at 54. The toggle link 122 has a cam surface 124 which cooperates with a cam roll 126 carried by the frame of the machine arranged to straighten the toggle links, upon rearward movement of the jack, against the action of a spring 128 (Fig. 2) connected between a forwardly extending projection 130 of the arm 114 and a pin in a boss carried by the projection 116. The initial rearward movement of the jack causes the slide 96 to be locked against downward movement by engagement of the pawl 112 with the ratchet 110, and as the toggle links 120, 122 are further straightened, which occurs preferably at the time when the toe end of the shoe moves beneath the leveling roll, the slide 96 is moved upwardly to force the pad 62 firmly against the cone of the last. The spring 128 snaps the toggle slightly past the straightened position in which it is held against collapse by a screw 132 carried by the link 120, which screw cooperates with a shoulder 134 on the toggle link 122. This toggle link has a tail 136 which engages the cam roll 126 at the completion of the leveling operation when the jack is moved back into the position shown in Fig. 1 at which time it is desirable to relieve the force exerted by the pad 62. Engagement of the tail 136 with the cam roll 126 causes the toggle to return to the position shown in which it is held by the spring 128 whereupon the shield 118 moves the pawl 112 out of engagement with the ratchet 110.

It will be understood that when the heel post is moved away from the toe post to adjust the jack for a larger size of shoe the bell crank lever 90 will be moved in a counterclockwise direction, as viewed in Fig. 1, thereby to move the cone support also away from the toe support about the axis of the pin 94. The movement of the cone support is proportioned to that of the heel support to move at a slower rate such that it will occupy the correct position lengthwise of the shoe regardless of the particular size of shoe which is to be operated upon. It is also desirable that the heightwise position of the pad 62,

when no shoe is located on the jack, be varied in accordance with the size of the shoe so that only a slight depression of the pad will be required upon placing a shoe on the jack. It will be understood that the heights of the cones of lasts of different sizes vary generally in accordance with the size so that for a larger shoe the pad 62 should occupy an initial lower position than for a small size shoe. The shoe shown in Fig. 1 represents the smallest size which the machine is capable of accommodating.

In order thus to vary the heightwise position of the cone support simultaneously with its adjustment lengthwise of the last the following mechanism is employed. A cam plate 138 (Figs. 1 and 3) is carried by one of the bars 66 of the holder 64 and is urged upwardly of the holder by a spring 140. This spring is connected at its upper end to a pin 142 on the holder and at its lower end to the cam plate 138 by a pin 144 extending through a slot 146 in the bar 66. A stud 148 passes through an open-ended slot in the upper end of the cam plate 138 and is threaded into the bar 66 to guide the upper end of the plate in its vertical movement as will be described. The cam plate is adjustably limited in its upward movement relatively to the holder 64 by a screw 150 threaded through a boss 152 extending laterally from the cam plate, the upper end of the screw engaging a head 154 on the pin 94. The pin 94 extends through a slot 156 in the lower portion of the cam plate 138 and thus guides the lower portion of the cam plate in its vertical movement. Thus it will be seen that the cam plate and the holder 64 will move as a unit about the pin 94 but that the holder and cam plate may partake of relative vertical movements.

On the lower end of the cam plate is provided a rearwardly extending foot 158 arranged for cooperation with a roll 160 on the boss 98. This foot normally engages the roll 160 when there is no shoe on the jack but during the downward movement imparted by the shoe to the pad 62 when the shoe is placed on the jack the foot 158 is moved downwardly below the roll, as shown in Fig. 1. Assume now that there is no shoe on the jack and that screw 44 is turned to move the heel support 10 away from the toe support to accommodate a shoe of larger size. The bell crank lever 84 is moved in a counterclockwise direction causing the holder 64 to swing about the pin 94 so that the supporting pad 62 moves away from the toe pad 34. The foot 158 of the cam plate 138 acting against the roll 160 will cause a downward movement to be imparted to the slide 96 and the holder 64 so that the pad 62 is moved downwardly upon adjustment of the jack for a larger size shoe. This compensates for the increase in the cone height of the last in the larger sizes. The extent of downward movement is such that the pad 62 will occupy a position somewhat higher than that which it occupies when a shoe is placed on the jack but by reason of the adjustment of the heightwise position of the pad the extent of downward movement thereof upon jacking the shoe is minimized.

The cam plate 138 is made separate from the holder 64 to prevent breakage of parts in the event that the operation of the leveling machine should be started without any shoe being placed on the jack and to permit adjustment by the screw 150 of the relative positions of the holder and cam plate when the foot 158 is in contact with the roll 160, and thus adjustment of the

initial position of the pad 62 in addition to the automatic adjustment of the pad heretofore described. Such adjustment is desirable to accommodate shoes of different styles. It will be understood that before a shoe is placed on the jack the foot 158 of the cam plate 138 bears against the roll 160. Normally the holder 64 with its cam plate 138 and the slide 96 are depressed when the shoe is placed on the jack so that when the slide 96 is subsequently moved upwardly, as heretofore described, to force the pad 62 firmly against the cone of the last, the foot 158 will not engage the roll 160. If, however, the slide 96 has not been depressed due to failure of the operator to place a shoe on the jack, and the jack is subsequently moved rearwardly, the slide 96 with the holder 64 can move upwardly with respect to the cam plate 138 by reason of the slidable connection therebetween. Were this not possible damage would occur to the machine because of the engagement of the foot 158 with the roll 160.

From the above it will be seen that I have devised a jack embodying heel and toe supports and an additional support for the cone of the last in which the relative positions of the parts are readily adjustable to take care of a wide range of sizes of shoes. With the arrangement disclosed herein a single jack may be employed for shoes of all sizes from children's up to men's large sizes.

Having thus described the invention, what I claim as new and desire to secure by Letters Patent of the United States is:

1. In a shoe-pressing machine, a jack for supporting a shoe for the application of pressure to the bottom thereof, said jack comprising a heel support, a toe support and an additional support for the shoe between the heel support and the toe support, means for relatively adjusting said heel and toe supports to accommodate shoes of different sizes, and means operated by said adjusting means for adjusting said additional support lengthwise of a shoe relatively to said heel and toe supports.
2. In a shoe-pressing machine, a jack for supporting a shoe for the application of pressure to the bottom thereof, said jack comprising a heel support, a toe support and an additional support for the shoe between the heel support and the toe support, means for relatively adjusting said heel and toe supports to accommodate shoes of different sizes, and means operated by said adjusting means for adjusting said additional support relatively to said heel and toe supports.
3. In a shoe-pressing machine, a jack for supporting a shoe for the application of pressure to the bottom thereof, said jack comprising a heel support, a toe support and an additional support for the shoe between the heel support and the toe support, means for relatively adjusting said heel and toe supports to accommodate shoes of different sizes, and means operated by said adjusting means for adjusting said additional support both heightwise and lengthwise of the shoe relatively to said heel and toe supports.
4. In a shoe-pressing machine, a jack for supporting a shoe for the application of pressure to the bottom thereof, said jack comprising a heel support, a toe support and an additional support for the shoe between the heel support and the toe support, means for relatively adjusting said heel and toe supports to accommodate shoes of different sizes, and means operated by said adjusting means for adjusting the heightwise position of said additional support.

5. In a shoe-pressing machine, a jack for supporting a shoe for the application of pressure to the bottom thereof, said jack comprising a heel support, a toe support and an additional support for the shoe between the heel support and the toe support, means for relatively adjusting said heel and toe supports to accommodate shoes of different sizes, means operated by said adjusting means for adjusting the heightwise position of said additional support, and other means for adjusting the heightwise position of said additional support to compensate for shoes of different styles.

6. In a shoe-pressing machine, a jack for supporting a shoe for the application of pressure to the bottom thereof, said jack comprising a heel support, a toe support, an additional support for the shoe between the heel support and the toe support, means for adjusting said heel support toward and away from said toe support, and means for adjusting said additional support in the same direction as that in which the heel support is adjusted but at a lesser rate.

7. In a shoe-pressing machine, a jack for supporting a shoe for the application of pressure to the bottom thereof, said jack comprising a heel support, a toe support, an additional support for the shoe between the heel support and the toe support, means for adjusting said heel support toward and away from said toe support, means for adjusting said additional support in the same direction as that in which the heel support is adjusted but at a lesser rate, and means operative in response to movement of the additional support away from the toe support for moving the additional support downwardly.

8. In a shoe-pressing machine, a jack for supporting a shoe for the application of pressure to the bottom thereof, said jack comprising a heel support, a toe support, an additional support for the shoe between the heel support and the toe support, means for adjusting said heel support toward and away from said toe support, and connections between said heel support and said additional support for moving said additional support in the same direction as that in which said heel support is moved but at a lesser rate.

9. In a shoe-pressing machine, a jack for supporting a shoe for the application of pressure to the bottom thereof, said jack comprising a heel support, a toe support, an additional support for the shoe between the heel support and the toe support, means for adjusting said heel support toward and away from said toe support, connections between said heel support and said additional support for moving said additional support in the same direction as that in which said heel support is moved but at a lesser rate, and means operative during said movement of the additional support for adjusting the heightwise position of the additional support.

10. In a shoe-pressing machine, a jack for supporting a shoe for the application of pressure to the bottom thereof, said jack comprising a heel support, a toe support, an additional support for the shoe between the heel support and the toe support, means for adjusting said heel support toward and away from said toe support, connections between said heel support and said additional support for moving said additional support in the same direction as that in which said heel support is moved but at a lesser rate, means operative in response to said movement of the additional support for adjusting the heightwise position of the additional support, and means for

additionally adjusting the heightwise position of the additional support independently of said movement of the additional support.

11. In a shoe-pressing machine, means for supporting a shoe at the heel end and at the forepart for the application of pressure to the shoe bottom, an additional support for the shoe between the heel end and the forepart movable to a position determined by the shoe by pressure of the shoe on said additional support, means for adjusting said supporting means to accommodate shoes of different sizes, means operated by said adjusting means for adjusting the initial heightwise position of said additional support prior to its contact by the shoe in accordance with the adjustment of said supporting means, and means for forcing said additional support more firmly against the shoe after it has been thus positioned by the shoe.

12. In a shoe-pressing machine, means for supporting a shoe at the heel end and at the forepart for the application of pressure to the shoe bottom, an additional support for the shoe between the heel end and the forepart movable to a position determined by the shoe by pressure of the shoe on said additional support, means for adjusting said supporting means to accommodate shoes of different sizes, means for simultaneously adjusting the initial heightwise position of the additional support prior to its contact by the shoe in accordance with the adjustment of said supporting means and for adjusting the position of the additional support lengthwise of the shoe relatively to said supporting means, and means for forcing said additional support more firmly against the shoe after the support has been positioned by the shoe.

13. In a shoe-pressing machine, a jack for supporting a shoe for the application of pressure to the bottom thereof, said jack comprising a heel support, a toe support, an additional support for the shoe between the heel support and the toe support, a slide between said heel and toe supports movable vertically relatively thereto, means pivotally mounting said additional support on said slide for adjustment lengthwise of the shoe relatively to said heel and toe supports, means for adjusting said heel support toward and away from said toe support, means connecting said heel support to said additional support to swing said support relatively to said slide thereby to move said additional support in the same direction as that in which said heel support is moved but at a lesser rate, and means operative during the swinging movement of said additional support for imparting vertical movement to said slide.

14. In a shoe-pressing machine, a jack for supporting a shoe for the application of pressure to the bottom thereof, said jack comprising a heel support, a toe support, an additional support for the shoe between the heel support and the toe support, a slide between said heel and toe supports movable vertically relatively thereto, means pivotally mounting said additional support on said slide for adjustment lengthwise of the shoe relatively to said heel and toe supports, means for adjusting said heel support toward and away from said toe support, means connecting said heel support to said additional support to swing said support relatively to said slide thereby to move said additional support in the same direction as that in which said heel

support is moved but at a lesser rate, means operative during the swinging movement of said additional support for imparting vertical movement to said slide, and means for moving said slide upwardly to force the additional support firmly against the shoe after the shoe has been positioned on the jack.
